F. H. MOORE

HEAT DISTRIBUTING HOOD

Filed Oct. 28, 1921

INVENTOR
Ford H. Moore.
BY *Arthur G. Brown*
ATTORNEY

UNITED STATES PATENT OFFICE.

FORD H. MOORE, OF KANSAS CITY, MISSOURI.

HEAT-DISTRIBUTING HOOD.

Application filed October 28, 1921. Serial No. 511,025.

To all whom it may concern:

Be it known that I, FORD H. MOORE, a citizen of the United States, residing at Kansas City, in the county of Jackson and State of Missouri, have invented certain new and useful Improvements in Heat-Distributing Hoods; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to surface heater hoods and particularly to a hood to be used in connection with a heater for applying heat to a surface such as asphalt and the like. In order to soften the asphalt for the road bed, it is usually the practice to apply heat over a relatively large area but to confine that heat within a given zone, and it is the purpose of my invention to provide an improved form of hood whereby an equal distribution of the heat may be maintained over a given area, so that there will be a uniform heat application to the asphaltum.

The novel construction of my invention will be apparent by reference to the accompanying drawings, in which

Fig. 1 is a perspective view of a hood constructed in accordance with my invention.

Fig. 2 is a vertical, longitudinal, sectional view through same, and

Fig. 3 is a view of the heat distributing baffles and casing protecting walls.

The casing or outer covering of the hood is in the form of a truncated pyramid, having inclined sides 1, 2, 3, and 4, bound at the bottom by reenforcing members, such as strap iron and the like, as indicated at 5 and at the top by a flange 6, reenforced by strap iron or similar material. Brackets 7, 8, 9, and 10 are carried by the respective walls, whereby the hood may be supported from the machine supplying the heat. The upper portion of the hood adjacent to the inlet opening 11 is reenforced by cast iron plates 12, 13, and 14 at one end and similar plates, generically designated 15, at the other end, the plates being fastened to the ends and side walls so that the heated gases directed through 11 will not burn the hood

covering, it being understood that the zone within the hood is hottest at this point.

Since the bottom of the hood extends over a considerable area and it is desired to provide a uniform heat distribution, I have arranged deflectors within the hood. The deflectors 16 and 17 are substantially inverted V-shape in cross section each comprising an inclined wall 18 and a substantially vertical wall 19. The deflectors are spaced apart, with their walls 19—19 substantially parallel so that a central space 20 will be provided, through which the heat may pass to the surface or pavement to be heated, and the walls or plates 18 are inclined preferably at a slightly greater angle than the walls 1 and 3 of the hood so that there will be flaring discharge ports 21 and 21' within the hood to direct the heated air over the pavement or surface to be heated.

In order to direct the heated air outwardly, the walls 18 are provided with inclined, depending extensions 22 and 23, as will be clearly seen in Fig. 2. The edges of the plates 13 and 14 for the protector structures will lie against the inclined edges of the plates or partitions 18, as seen in Fig. 2, and thereby thoroughly protect both the end and side walls of the hood.

I prefer cast iron as a reenforcing plate for the reason that it best resists the high temperatures and because it is inexpensive to use in a structure of this kind. I have found in actual practice that the heat will be directed through the central transverse opening 20 to impinge upon the surface to be heated and that a uniform temperature will be applied to the entire area confined within the bounds of the hood. The structure is inexpensive to manufacture and will efficiently distribute the heat over the desired area.

What I claim and desire to secure by Letters-Patent is:

A hood for paving machines comprising a casing in the form of a truncated pyramid, the top of which is provided with a heat inlet opening, inverted V-shaped partitions within the hood and adjacent to the opening to provide a central heat passage way, and two end heat passage ways to distribute the heat uniformly within the hood.

In testimony whereof I affix my signature.

FORD H. MOORE.
